UNITED STATES PATENT OFFICE.

SYLVESTER D. SHOEMAKER, OF GROGAN, OHIO.

SHEET-METAL GUTTER.

No. 882,801.

Specification of Letters Patent. Patented March 24, 1908.

Application filed July 19, 1907. Serial No. 384,562.

To all whom it may concern:

Be it known that I, SYLVESTER D. SHOEMAKER, citizen of the United States, residing at Grogan, in the county of Franklin and State of Ohio, have invented certain new and useful Improvements in Sheet-Metal Gutters, of which the following is a specification.

My invention relates to sheet metal gutters and has for its object, the provision of a sheet metal gutter constructed in such manner that an unbroken water-way is provided therethrough without weakening the structure or causing the metal to become unduly distended or cracked.

Further objects and advantages of the invention will be set forth in the detailed description which now follows.

In the accompanying drawing: Figure 1 is a plan view of a portion of a sheet metal gutter corner, Fig. 2 is a vertical section thereof upon line $y-y$ of Fig. 1, and, Fig. 3 is a vertical section thereof upon line $x-x$ of Fig. 1.

Like numerals designate corresponding parts in all of the figures of the drawings.

Attempts have been made heretofore to stamp out a gutter corner such as is shown in the drawing, and to make said corner a rounded one in order to provide a continuous and unbroken water-way for the passage of the water, but it has been found that where these gutters are stamped out under comparatively little pressure, they buckle and form ridges at the corners, said ridges tending to obstruct the passage of leaves, twigs and the like and ultimately stopping up the gutter, while when the pressure is sufficient to force out all of these ridges, it is great enough to so distend and strain the metal, that it is often broken and always so thin that it easily rusts through, for even though these gutters are made of galvanized metal, corrosion will set in around the least crack formed in the metal by undue strain. It is to provide a gutter having all of the advantages of a continuous and unbroken water-way with none of the disadvantages incident to undue strain upon the metal, that the present invention is particularly designed.

In the drawing, the numerals 5 and 6 designate the gutters stamped out of the corner piece 7. The die from which this piece is stamped, is so arranged as to form a portion 8, narrow at the top and gradually widening toward the bottom, which is curved to conform to the curvature of the gutter

and which lies substantially at an angle of 45 degrees to either the gutter 6 or the gutter 5. At the outside edge a portion 9 is formed in the gutter, which also lies substantially at an angle of 45 degrees to the gutters 5 and 6, and which likewise conforms to the curvature of the gutter (see Fig. 2). By forming these angularly disposed portions 8 and 9, the true curvature of the gutter is preserved without the formation of any ridges and without unduly straining the metal.

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims.

What I claim, is:

1. A stamped sheet metal gutter having substantially semi-circular portions in cross section which lie at right angles with each other and portions which lie at an angle to both of the first named portions the latter portions exhibiting a straight line in horizontal section.

2. In a device of the character described the combination with gutter portions which lie substantially at right angles with each other and which exhibit a substantially semi-circular cross section of connecting members located at the juncture of said gutter portions said connecting members exhibiting a straight line in horizontal section, and said members being tapering.

3. In a device of the character described, the combination with gutter portions which lie substantially at right angles with each other and which exhibit a substantially semi-circular cross section, of a connecting member which lies at an angle to both of the gutter portions, said connecting member exhibiting a straight line in horizontal section and said connecting member being narrow at the top and wide at the bottom.

In testimony whereof I affix my signature in presence of two witnesses.

SYLVESTER D. SHOEMAKER.
